ENCLOSED CASE MUD PERCUSSION TOOL
Ross Bassinger, Rte. 11, Box 588, San Antonio, Tex.
Filed Jan. 19, 1960, Ser. No. 3,300
16 Claims. (Cl. 173—73)

This invention relates to new and useful improvements in percussion tools powered by a non-compressible hydraulic fluid.

Rotary bits, jars and other tools having reciprocating high speed percussion elements operated by an incompressible hydraulic fluid have been widely in quarrying stone, drilling oil and gas wells through hard formations and in other applications. The percussion mechanism of such tools are of two general types; (1) those in which valves or percussion elements are spring actuated, and (2) those in which one surface of a piston driving a hammer in the tool is exposed to constant fluid pressure for driving it in one direction while another opposed larger surface is exposed to intermittent fluid pressure for driving it in the other direction with the admission of fluid pressure to the larger surface controlled by movement of the piston.

Each of these general types of tools has certain disadvantages. For example, springs become fatigued, break and have to be replaced frequently when subjected to tension or compression at a speed of many hundreds of times per minute. Differential piston type tools, as typified by U. S. Patent 1,096,886, eliminate the necessity for springs to operate valves or hammers but have a tendency to trap incompressible hydraulic fluid between the hammer and anvil forming essential parts of such tools, thus cushioning the hammer blow and decreasing its effectiveness.

It is an object of this invention to provide an improved percussion tool operated by an incompressible hydraulic fluid in which cushioning of a hammer blow cannot occur.

Another object is to provide a percussion tool operated by incompressible hydraulic fluid in which spring actuation of hammer and valves is eliminated.

Another object is to provide a percussion tool in which build up of solids that may be present in the actuating hydraulic fluid on the opposed faces of hammer and anvil is substantially eliminated.

Another object is to provide a tool of this class that may be operated at high speeds with little fatigue of valves and percussion elements.

Another object is to provide a tool of this class in which light weight long wearing hydraulic fluid operated reciprocating valves of improved design give positive control of hydraulic fluid pressure applications.

Another object is to provide a tool of this class which is operable at high speeds with substantially no water hammer.

Still another object is to provide a tool of this class having a reciprocating finger valve disposed to open and close an outlet for hydraulic fluid from the tool in which the finger valve is hydraulically and positively prevented from entering and closing the outlet passage until after the hammer has struck the anvil.

Other objects, advantages and features of this invention will be apparent to one skilled in the art upon a

2

consideration of the written specification, the attached claims and annexed drawings.

In the drawings, wherein like reference characters are used throughout to designate like parts:

5 FIGS. 1 and 2 are vertical sections through a preferred embodiment of this invention. FIG. 1 illustrates an upper part of the tool and FIG. 2 a lower part of the same tool, FIG. 2 being a continuation of and to be considered as joined to the lower end of FIG. 1;

10 FIGS. 3, 4 and 5 are vertical sections through a modification of this tool and illustrate sequential parts of a hammer stroke and show the valve and conduit relationships at sequential parts of the stroke.

The tool illustrated in FIGS. 1 and 2 comprises a housing designated generally by the reference numeral 1. For convenience in manufacturing, this housing preferably is made of three parts; a short upper sub 2, an adjoining thick-walled section 3, and a lower thin-walled section 4.

15 The upper part of sub 2 preferably is formed as a tool joint pin 5 having threads 6 suitable for connection to a drill string. Sub 2 has a conduit 7 for entrance of hydraulic fluid under pressure, which preferably leads to a cavity 8 in the sub which in turn communicates through several conduits 9 with a space 11 within the upper part of the thick-walled upper section 3. Sub 2 and section 3 preferably are joined by tapered threads as illustrated at 12.

20 A cylinder 13 of proper size to fit snugly upon a smaller piston 14 of a reciprocating finger valve designated generally as 15 is disposed in sub 2 and communicates with the exterior of the tool through a purge duct 16.

25 In cavity 11, in the upper end of thick-walled section 3, an annular spacer ring 17 having openings 18 therethrough is disposed and is held in place by a spring 19.

30 Annular spacing ring 18 and spring 19 eliminate the necessity for close tolerance in the manufacture of the joint between sub 2 and the upper thick-walled section 3. Spacer ring 18 serves as a limit for the reciprocating travel of finger valve 15 in a downward direction by supplying a surface which stops the valve by contact with shoulder 21 on the valve. Variation or adjustment in the effective length of the finger valve may be easily accomplished by changing spacer ring 18 for a ring of somewhat different thickness. Spring 19 functions merely to hold spacer ring 18 in firm contact with a shoulder 22 formed on the upper thick-walled section 3 and is not subjected to flexion by movement of hammer 25. A finger portion 24 of valve 15 is slidably disposed through an opening in spacer ring 17.

35 A hammer designated generally as 25 is slidably disposed within housing 1 for reciprocating movement. Hammer 25 comprises a smaller piston portion disposed in the bore of thick-walled portion 3 and having an annular face 27 constantly exposed to pressure of actuating hydraulic fluid entering the tool through conduit 7, chamber 8, conduit 9, space 11 and openings 18. Hammer 25 also has a larger piston portion 28, shown in FIG. 2, slidably in the larger bore of thin-walled section 4 of the housing. Hammer 25 also has a portion of lesser diameter 29 below piston 28.

40 45 50 55 60 65 70 75 80 85 90 95 Pistons 26 and 28 serve to keep the hammer axially aligned during reciprocating motion in addition to furnishing surfaces against which hydraulic fluid under pressure may act. Since hammer portion 29 below piston 28 is

of smaller diameter than the bore of housing section 4, it leaves an unoccupied space 31 within the housing around this portion of the hammer and forms a continuation of the space between the hammer and anvil.

A passageway for hydraulic fluid extends through the hammer and comprises an upper portion 32 and branch conduits 33 extending from the lower end of upper portion 32 to the space 31 surrounding part 29 of the hammer. The passageway through the hammer with an upper central portion 32 and several, preferably three, branch conduits 33 connecting with the space 31 in the housing surrounding the lower part of the hammer at some distance above the beating face of the hammer as illustrated, eliminates much susceptibility to metallic fatigue and failure of the lower part of the hammer due to this cause. Finger valve 15 and portion 32 of the passageway are so disposed that finger 24 of the finger valve will enter passageway 32 in response to positioning of the hammer near the end of its up stroke and substantially close the passageway to fluid flow.

In the lower end of hammer 25, a cavity 34 is formed, having an upper concentric cylindrical portion 35. A reciprocating finger valve 36 is disposed within this cavity and is retained therein by an annular nut 37 which may be threaded as shown, or held in place by snap rings or other convenient device.

Finger valve 36 has an upper piston portion 39 disposed slidably in cylinder 35, a shoulder portion 42, adapted to limit reciprocating movement of the finger valve, disposed for reciprocation in cavity 34, and a lower finger portion 43 of larger diameter than piston 39 and slidably disposed in retaining nut 37. The lower finger 43 preferably is hollow with its hollow interior inwardly tapering toward shoulder 42 in order to reduce weight of the valve and to prevent metallic fatigue. A purge passage 44 extends longitudinally through the valve stem and provides a passageway for fluid communicating with the hollow interior of finger 43 and with cylinder 35 behind piston 39. Cylinder 35 communicates with the interior of housing 1 at a point above piston 28 of the hammer via a purge passageway 45.

An anvil designated generally as 47 is slidably disposed within the lower end of housing 1 for reciprocating travel. Anvil 47 is constructed with a piston section 48 fitting the interior of housing 1 and has a face 49 adapted to be struck by hammer 25. Splineways 50 are formed in the lateral surface of the hammer below piston 48 in radial alignment with splineways 51 in the lower end of housing 1. Bearings 52 are disposed within the splineways and permit relative longitudinal movement between the anvil and housing while preventing relative rotation therebetween.

The lower end of the housing 53 is equipped with suitable means for attaching to a tool 55 here shown as threads 54. A passageway for operating hydraulic fluid extends from the face of the anvil 49 through the anvil and tool to a point adjacent to a work surface. Passageway 56 is axially aligned with finger 43 of valve 36 so that finger 43 may move forward to enter and substantially close passageway 56 when pressure in passageway 56 is sufficiently reduced.

A means for hydraulically preventing entrance of finger 43 into passageway 56 until after hammer 25 has struck the anvil in its reciprocating travel is provided. This means comprises grooves 57 cut into the face of the hammer. These grooves preferably are three in number and are radially disposed to communicate with passageway 56 and with space 31 in the housing around the hammer and below piston 28. The grooves are located at the striking interface of the hammer and anvil, and should have a total cross-sectional area amounting to about 90 percent of that of passageway 56, plus or minus 5 percent, depending upon the type of fluid used. If desired, grooves 57 could be located in the anvil face, or be formed as aligned grooves in both hammer and anvil.

The operation of this tool may be best understood by considering FIGS. 3, 4 and 5 which illustrate a tool substantially identical with that just described in FIGS. 1 and 2, except that spring 19 in cavity 11 is omitted.

FIG. 3 illustrates the position of the parts of the tool at the instant after impact of the hammer with the anvil. Incompressible hydraulic fluid, preferably drilling mud, may be considered as entering through supply conduit 7, cavity 8, conduits 9, cavity 11 and openings 18 into the interior of housing 1. The full operating pressure is thus applied against the lower surface of upper finger valve 15, driving the valve upward to the full limit of its reciprocating travel and holding it in raised position. There is also some flow of operating fluid through the longitudinal 15 purge passage in the stem of valve 15 into cylinder 13 and to the exterior of the tool through vent 16. Flow of fluid through the purge passage in the valve stem, cylinder 13 and vent 16 substantially eliminates water hammer, maintains pressure in cylinder 13 between the pressure at which operating fluid is supplied and that at the outside of the tool, purges cylinder 13 of any accumulation of solid particles, and insures substantially constant flow from cylinder 13 to the outside of the tool, thus preventing sand, rock chips and other abrasive matter from being drawn into cylinder 13.

Pressure of actuating fluid in the body cavity is applied through passageway 32 in the hammer and branch passageways 33 to the space 31 around the lower part of the hammer within casing 1 and from this space through openings 38 into cavity 34 in the lower part of the hammer.

In the position of parts shown, pressure from the fluid flowing through passageway 56 in the anvil has just been reduced by contact of opposing faces of the hammer and anvil. Flow of actuating fluid through grooves 57 has effectively prevented trapping incompressible hydraulic fluid between the hammer and anvil faces but upon contact of the faces the restriction of flow area to that of the total cross section of these grooves has resulted in a pressure drop in conduit 56.

Full pressure of operating fluid however is upon cavity 34 and upon the upper side of the shoulders of the finger valve disposed therein. A part of this pressure tending to drive the finger valve down into closing position in passageway 56 is balanced by pressure in the opposite direction upon the lower side of piston 39, but the lower end of the valve finger has an area much larger than that of piston 39. The reduction in pressure upon the lower end of the valve finger caused by contact of the hammer and anvil faces with resulting restriction in flowway cross section has caused the finger valve to be driven into and substantially close passageway 56.

With the parts in the position shown in FIG. 3, actuating pressure thus is applied via passageway 32 and branch passageways 33 in the hammer through space 31 in the housing and grooves 57 to the face of the hammer and piston 28 driving the hammer upward toward the position shown in FIG. 4. At the instant before the upward travel of the hammer causes passageway 32 in the hammer to contact the lower end of the upper finger valve, the lower end of the lower finger valve is drawn out of passageway 56 by hammer travel. Operating pressure thus comes upon the lower end of the lower finger valve and the valve is lifted.

As soon as the lower end of the upper finger valve cuts off flow through passageway 32, there is a drop of pressure therein and the operating pressure exerted on the shoulder of upper finger valve 15, assisted by small pressure in cylinder 13, drives the valve downward.

With the upper finger valve in passageway 32, the operating pressure is applied to the annular surface 27 of the smaller upper piston of the hammer thus arresting its upward motion and starting the hammer on its power stroke. As the hammer travels downward in its power stroke, it is necessary that the incompressible hydraulic

fluid be moved outward through passageway 56 from the space between the decending hammer face and opposing anvil face.

Since this fluid has some viscosity and inertia there will be back pressure upon the lower end of the lower finger valve which is sufficient to keep the valve in raised position. At the same time, there is a flow of some of this fluid through the longitudinal purge passage in the valve stem and outward through vent 45 into a space in the housing above piston 28. Since this space is variable in size according to the position of the hammer, flow of liquid upward through the purge channel and vent into this space and outward through openings 60 and 61 in the body substantially eliminate entrance of sand, stone chips and other abrasives through openings 60 and 61 in the housing 1. The parts remain in the relative position shown in FIG. 4 until the instant before the hammer strikes the hammer face.

At this instant hammer travel disengages passageway 32 from the lower end of the upper finger valve 15 and pressure again builds up in passageway 32, branch passageways 33, space 31, passage 38, space 34, grooves 57 and in the narrow space between the anvil and hammer. This hydraulic pressure effectively and positively maintains the lower finger valve in its raised position and prevents its engagement with passageway 56 in the anvil until after the hammer has struck the anvil. At the instant the hammer strikes the anvil, flow of fluid into passageway 56 and pressure below the lower end of the lower finger valve is restricted because of the smaller area of grooves 57 as compared to the cross-sectional area of passageway 56. Grooves 57 also function at this time to draw off fluid between contacting faces of the hammer and anvil without any cushioning effect due to retained fluid between these surfaces.

Reduction of pressure below the finger valve is not accompanied by reduction of pressure in cavity 34 and therefore the unbalanced part of the force applied by the fluid to the shoulder of the lower finger valve drives it downward into passageway 56 at very high speed, cutting off flow of fluid therethrough, and the cycle of operations is repeated.

It will be seen that in addition to effectively preventing any cushioning of hammer blows upon the anvil face, the provision of withdrawing fluid from between the faces made by continuation of flow through grooves 57 permits the faces to be scoured by fluid extruded from between them. This scouring action of the drilling mud is especially important when it may contain grit or other materials which might build up into hard deposits under the force of hammer impacts. If allowed to accumulate such deposits frequently cause spalling or other deterioration of the striking surfaces. Build up of deposits and spalling are effectively prevented in the tool of this type.

The purge passageways in the valve stems of both valves permits flow of fluid through their respective cylinders and so prevent accumulation of deposits in these cylinders and entrance of abrasive particles. This purge passageway also is effective in reducing water hammer.

The particular design of finger valve used has been found to be very effective in reducing metallic fatigue so that the valves are long wearing under severe operating conditions.

The velocity of valve travel in reciprocation can be predetermined by choosing a size of cross-sectional area for vent passageways 45 which gives the required speed of valve operation while reducing the impact load.

From the foregoing it will be seen that this invention is one well adapted to attain all of the ends and objects hereinabove set forth, together with other advantages which are obvious and which are inherent to the apparatus.

It will be understood that certain features and subcombinations are of utility and may be employed without

reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A hydraulic percussion tool comprising in combination a housing; an anvil slidably disposed in an end of the housing; a hammer slidably disposed within the housing for reciprocating movement to beat upon the anvil, said hammer having a first piston surface constantly exposed to hydraulic pressure tending to drive it in one direction and a second larger piston surface intermittently exposed to hydraulic pressure to drive it in the opposite direction; a supply conduit for hydraulic fluid under pressure disposed to introduce said fluid into a space in the housing behind the first piston; a passageway for hydraulic fluid through the hammer, communicating with said space behind the first piston and with a second space within the housing beyond the second piston and between the hammer and anvil; a reciprocating hydraulically actuated finger valve, responsive to position of the hammer, disposed to enter and substantially close said passageway near the end of the back stroke of the hammer and disposed for sufficient length of reciprocal travel to remain in said passageway during a substantial part of the power stroke of the hammer; a second passageway for hydraulic fluid through the anvil, communicating with the space in the housing between the hammer and anvil and with the exterior of the tool; a second hydraulically actuated reciprocating finger valve carried by the hammer in position to move into and substantially close the passageway through the anvil after contact of the hammer and anvil; and hydraulically actuated means for preventing movement of said second finger valve into the passageway through the anvil until contact of hammer and anvil occurs.
2. The tool of claim 1 wherein the hydraulically actuated means for preventing movement of the second finger valve into the second passageway comprises a third flowway, having lesser cross-sectional area than the passageway through the anvil, leading from the space behind the second piston to the passageway through the anvil, disposed where it is not closed by contact of hammer and anvil but is closed by the finger valve on movement of the valve into the second passageway.
3. The tool of claim 2 wherein the flowway is a plurality of radial grooves located at the interface of hammer and anvil.
4. The tool of claim 3 wherein the flowway is a plurality of radial grooves in the hammer face.
5. The tool of claim 4 wherein the radial grooves have a total cross-sectional area amounting to about 90 percent of cross-sectional area of the passageway through the anvil.
6. The tool of claim 1 wherein each of the reciprocating finger valves is disposed in a valve retaining member and comprises a smaller piston disposed in a cylinder communicating with the exterior of the tool through a vent passageway entering the cylinder at a point further within the cylinder than that reached by the piston at its maximum distance of travel and a finger slidably in said valve retaining member, said finger having a larger piston surface than the surface of the smaller piston opposed to the smaller piston surface; a shoulder on said finger part disposed in a cavity between said valve retaining member and said cylinder and having an annular effective area equal to the difference between the area of the piston surface of the finger and the area of the smaller piston exposed to pressure of fluid within the cavity; a stem connecting said smaller piston and said finger, said stem having a purge passageway therethrough extending through said finger, through said smaller pis-

ton, and communicating with said cylinder behind the smaller piston; and means for varying pressure on the larger piston surface on the finger part, and on said annular area on said shoulder responsive to movement of the hammer to cause reciprocation of the finger.

7. The tool of claim 1 wherein the second reciprocating finger is disposed in a valve retaining member carried by the hammer, and the valve comprises a smaller piston disposed for reciprocation in a cylinder in the hammer communicating with the exterior of the tool through a vent passageway connecting the cylinder, at a point further within the cylinder than that reached by the smaller piston at its limit of travel, with a space within the body around the hammer between the piston surfaces of the hammer, and through openings in the body communicating with said space; a finger slidable in the valve retaining member and having a larger piston surface opposed to the smaller piston; a shoulder on the finger disposed in a cavity in the hammer between the valve retaining member and the cylinder and having an annular area equal to the difference in area between the area of the piston surface of the finger and the area of the smaller piston exposed to pressure of fluid within the cavity; a stem connecting the smaller piston and the finger; a purge passageway extending longitudinally through the stem, finger and smaller piston communicating with the interior of the cylinder behind the piston; and means, comprising openings from the cavity into a space in the body surrounding the striking end of the hammer, for varying pressure on the larger piston surface and on said annular area of the shoulder, responsive to movement of the hammer, to cause reciprocation of the finger.

8. The tool of claim 1 wherein each of the reciprocating finger valves is disposed in a valve retaining member and comprises a smaller piston disposed in a cylinder communicating with the exterior of the tool through a vent passageway entering the cylinder at a point further within the cylinder than that reached by the piston at its maximum distance of travel; a finger slidable in said valve retaining member, said finger having a larger piston surface than the surface of the smaller piston, opposed to the smaller piston surface; a shoulder on said finger part disposed in a cavity between said valve retaining member and said cylinder and having an annular effective area equal to the difference between the area of the piston surface of the finger and the area of the smaller piston exposed to pressure of fluid within the cavity; a stem connecting said smaller piston and said finger, said stem having a purge passageway therethrough extending through the finger, through said smaller piston, and communicating with said cylinder behind the piston; and means for varying pressure on the larger piston surface on the finger part, and on said annular area on said shoulder responsive to movement of the hammer to cause reciprocation of the finger.

9. The tool of claim 1 wherein the second reciprocating finger is disposed in a valve retaining member carried by the hammer, and the valve comprises a smaller piston disposed for reciprocation in a cylinder in the hammer communicating with the exterior of the tool through a vent passageway connecting the cylinder, at a point further within the cylinder than that reached by the smaller piston at its limit of travel, with a space within the body around the hammer between the piston surfaces of the hammer, and through openings in the body communicating with said space; a finger slidable in the valve retaining member and having a larger piston surface opposed to the smaller piston; a shoulder on the finger disposed in a cavity in the hammer between the valve retaining member and the cylinder and having an annular area equal to the difference in area between the area of the piston surface of the finger and the area of the smaller piston exposed to pressure of fluid within

the cavity; a stem connecting the smaller piston in the finger; a purge passageway extending longitudinally through the stem, finger and smaller piston communicating with the interior of the cylinder behind the piston; and means, comprising openings from the cavity into a space in the body surrounding the striking end of the hammer, for varying pressure on the larger piston surface and on said annular area of the shoulder responsive to movement of the hammer to cause reciprocation of the finger.

10. In a hydraulic percussion tool wherein a hammer is slidably disposed in a housing to beat upon an anvil, said hammer having a piston surface tending to move the hammer away from the anvil upon which hydraulic pressure is alternately increased and diminished to cause reciprocation of the hammer, and means for intermittently admitting hydraulic fluid to press upon said piston surface is provided, the improvement which comprises an outlet passageway for hydraulic fluid through the anvil; a hydraulically actuated reciprocating finger valve mounted in the hammer and disposed to move into and close the passageway through the anvil upon contact of the hammer with the anvil; and hydraulic means for preventing movement of said finger valve into said passageway through the anvil until contact of hammer and anvil occurs.

11. The tool of claim 10 wherein the hydraulic means for preventing movement of the finger valve into the passageway comprises a fluid flowway, having lesser cross-sectional area than the passageway through the anvil, communicating with the passageway through the anvil and with a space within the housing between the anvil and said piston so disposed that it is not closed by contact of hammer and anvil but is closed by the finger valve on movement of the valve into the passageway through the anvil.

12. The tool of claim 11 wherein the flowway is a plurality of radial grooves located at the interface of hammer and anvil.

13. The tool of claim 11 wherein the flowway is a plurality of radial grooves in the hammer face.

14. The tool of claim 11 wherein the radial grooves have a total cross-sectional area amounting to about 90 percent of the cross-sectional area of the passageway through the anvil.

15. The tool of claim 11 wherein the finger valve mounted in the hammer comprises a smaller piston portion disposed in a cylinder in the hammer, said cylinder communicating with the exterior of the tool through a vent passageway entering the cylinder at a point further within the cylinder than that reached by the piston at its maximum distance of travel; a finger portion slidably disposed in a valve retaining member in said hammer, said finger portion having a larger piston surface than the surface of the smaller piston opposed to the smaller piston surface; a shoulder on said finger part disposed in a cavity within the hammer between said valve retaining member and said cylinder, said shoulder having an annular effective piston area equal to the difference between the area of the piston surface of the finger and the area of the smaller piston, exposed to pressure of fluid in the cavity; a stem connecting said smaller piston and said finger, said stem having a purge passageway therethrough extending through said finger, through said smaller piston and communicating with said cylinder behind the piston; and means for varying pressure on the larger piston surface of the finger part, and on said annular area on said shoulder, responsive to movement of the hammer, to cause reciprocation of the finger.

16. In a hydraulic percussion tool wherein a hammer is slidably disposed in a housing to beat upon an anvil, said hammer having a piston surface tending to move the hammer away from the anvil upon which hydraulic pressure is alternately increased and diminished to cause reciprocation of the hammer, and means for intermittently

ly admitting hydraulic fluid to press upon said piston surface is provided, the improvement which comprises structure including a portion of said housing extending around and enclosing said hammer and a portion of said anvil and supporting said anvil in sliding relationship within the lower end of said housing, annular passageway means within said housing around the lower portion of said hammer and the upper portion of said anvil, a cavity formed in the lower portion of said hammer, passage means through said hammer connecting said cavity and 10 said annular passageway, an outlet passageway for hydraulic fluid through the anvil, a hydraulically actuated reciprocating finger valve mounted in said cavity extending through the lower end of the hammer and disposed to

move into and close the passageway through the anvil upon contact of the hammer with the anvil, and hydraulic means for preventing movement of said finger valve into said passageway through the anvil until contact of hammer and anvil occurs.
